US00D720633S

(12) **United States Design Patent**
Novotny et al.

(10) **Patent No.:** US D720,633 S
(45) **Date of Patent:** ** Jan. 6, 2015

(54) **THERMOSTAT**

(71) Applicant: **Honeywell International Inc.**,
Morristown, NJ (US)
(72) Inventors: **Josef Novotny**, Kuncina (CZ); **Eugene J. Takach**, Eden Prairie, MN (US); **Matt Goulet**, Bloomington, MN (US); **Arnie Kalla**, Maple Grove, MN (US); **Tomas Losak**, Breclav (CZ)

(73) Assignee: **Honeywell International Inc.**,
Morristown, NJ (US)

(**) Term: **14 Years**

(21) Appl. No.: **29/470,925**

(22) Filed: **Oct. 25, 2013**

(51) LOC (10) Cl. **10-04**

(74) Attorney, Agent, or Firm — Seager Tufte & Wickham LLC.

CLAIM

(57) The ornamental design for a faceplate for thermostat, as shown and described.

DESCRIPTION

FIG. 1 is a perspective view of a faceplate for thermostat in accordance with the present invention;

FIG. 2 is a front side view of the faceplate for thermostat of FIG. 1;

FIG. 3 is a right side view of the faceplate for thermostat of FIG. 1;

FIG. 4 is a left side view of the faceplate for thermostat of FIG. 1;

FIG. 5 is a top side view of the faceplate for thermostat of FIG. 1; and,

FIG. 6 is a bottom side view of the faceplate for thermostat of FIG. 1.

The portions illustrated in broken lines on the figures are for illustrative purposes only and form no part of the claimed design.

1 Claim, 6 Drawing Sheets
